UNITED STATES PATENT OFFICE.

ABRAHAM NOVICK, OF NEW YORK, N. Y., ASSIGNOR TO UNITED STATES ENVELOPE COMPANY, OF SPRINGFIELD, MASSACHUSETTS, A CORPORATION OF MAINE.

BLANK-FORMING MECHANISM.

1,303,371.

Specification of Letters Patent. Patented May 13, 1919.

Original application filed October 17, 1913, Serial No. 795,629. Divided and this application filed August 13, 1917. Serial No. 185,836.

To all whom it may concern:

Be it known that I, ABRAHAM NOVICK, a citizen of the United States, residing at New York, in the county of Kings and State of New York, have invented certain new and useful Improvements in Blank-Forming Mechanism, of which the following, together with the accompanying drawings, is a specification.

10 The present invention relates to a blank forming mechanism, and has particular reference to mechanism of that class for use in an envelop machine.

The present application is a continuation 15 of my allowed and subsequently abandoned application Serial No. 55,356, (series of 1915) said application being a renewal of my forfeited application Serial No. 825,217 (series of 1900). The present application, 20 like my previous application above referred to, from which the present application is continued, is a division of my original application Serial No. 795,629 (series of 1900), filed October 17, 1913.

25 The present invention contemplates the production of blanks, substantially parallelogrammic in form, from a continuously moving web of material, such as paper or cardboard. The blanks are cut on the bias

30 from the web, so as to economize stock and reduce the waste to a minimum. The invention contemplates the further advancement of each blank thus separated from the web, for the purpose of performing subsequent

35 gumming and folding operations thereon by mechanisms which form no part of the present invention; to this end, the direction of motion of successively severed blanks is gradually changed while the blanks are in 40 transit, so as to center and square them with reference to their direction of motion, and thereby bring one axis of the blank in line with said direction of motion.

The above and other objects are attained 45 by the construction which is set forth in detail hereinafter, reference being had in this connection to the accompanying drawings, in which—

Figure 1 is a plan view of mechanism 50 which illustrates my invention.

Fig. 2 is a side elevation of the same.

Fig. 3 is a partial vertical sectional view, in the plane of the line 3—3, Fig. 1.

Fig. 4 is a detached view of a cutting cylinder.

Fig. 5 is the development of the surface of the cylinder which is represented in Fig. 4.

Fig. 6 is a detached view of another cutting cylinder.

Fig. 7 is a transverse sectional view of the cylinder which is represented in Fig. 6.

Figs. 8 and 9 are plan and side views respectively of one of the cutters carried by the cylinder of Fig. 4 for forming the edge 65 cuts in the traveling web.

Fig. 10 is a sectional view of the cutter which is shown in Figs. 8 and 9.

Fig. 11 is a detached view showing a modified form of cutting cylinder, which 70 combines the functions of the two cylinders shown in Figs. 4 and 6.

Fig. 12 is the development of the surface of the cylinder which is shown in Fig. 11.

Fig. 13 is a diagrammatic view illustrating the steps which occur in the formation and change of direction of an envelop blank in the machine embodying this invention.

Like reference characters refer to like parts in the different figures.

The operative parts of my improved mechanism are represented in the present instance as mounted on a suitable table 1, which has supporting legs 2, 2. The table 1 supports a pair of longitudinal side frames 3 and 4, and substantially at right angles to the latter a pair of transverse side frames 5 and 6. Power is imparted to the mechanism from a suitable source, not shown, by means of a belt pulley 7 on main driving 90 shaft 8, the latter being suitably journaled in the side frame 3. The shaft 8 carries a pinion 9 which is in mesh with a gear 10 on a countershaft 11, also journaled in the side frame 3. Above the shaft 11 is journaled a shaft 12, which is driven from the shaft 11 by means of intermeshing gears 13 and 14. The gear 14 on shaft 12 serves to actuate the web-advancing and blank-cutting devices of my mechanism, as hereinafter described.

The continuous web, as indicated at A,

Figs. 1 and 3, is taken from a roll, not shown, and is continuously forwarded between the bight of feed rolls 15 and 16 which are carried on shafts 17 and 18 respectively having suitable bearings in the frames 3 and 4. Said shafts carry intermeshing gears 19 and 20, the first named gear being also in mesh with the gear 14 on shaft 12, whereby the feed rolls 15 and 16 are rotated in unison, continuously, to move the web A forward. In advance of said feed rolls are provided cutting cylinders 21 and 22, which are carried on shafts 23 and 24 respectively having suitable bearings in the side frames 3 and 4. Said shafts carry intermeshing gears 25 and 26, the first named gear being in mesh with the gear 14 on shaft 12, whereby the cutting cylinders 21 and 22 are driven in the same direction, relatively, as the forward rolls 15 and 16.

The cutting cylinder 22, in the present instance, is constructed as represented in Figs. 4 and 5. Said cylinder carries at each end thereof a pair of cutters 27, 27, for making the notches 28 in the edge of the traveling web A, as shown in Fig. 13. Said cylinder 22 also carries a centrally disposed cutter 29, for making at each revolution a center cut 30 in the web, as shown in Fig. 13. The cutters 27 and 29 of cylinder 22 coöperate with the surface of cylinder 21 in making the four edge cuts 28 and the single center cut 30 in the web at each revolution, the surface of cylinder 21 being preferably hardened for this purpose. The pieces or chips of the web A which are defined by these cutting operations do not become entirely separated from the web on account of the fact that some of the fibers of the material remain unsevered, and it is usually necessary to employ a mechanism for removing these partially separated chips from the traveling web.

Such a chip removing mechanism may take any suitable form, such as that shown in my copending application Serial No. 798,236, filed October 30, 1913. The details of such mechanism constitute no part of the present invention, and hence a description thereof is unnecessary; I have indicated a pair of chip removing rolls 31 and 32 which are mounted on shafts 33 and 34 respectively, having intermeshing gears 35 and 36. The latter of said gears is in mesh with an intermediate gear 37 which is driven from the gear 25 of chip cutting cylinder 21, so that the removing cylinders 31 and 32 with their coöperating chip removing devices 38 and 39, Fig. 3, are driven in the same direction relatively as the feed rolls and the chip cutting cylinders, to remove successive chips from the traveling web in the manner set forth in my aforesaid copending application Serial No. 798,236, or in any other well known manner.

It is to be understood that said chip removing devices are operable with respect to the crips cut from the edges of the web, at 28, as well as the chips cut from the center of the web at 30, Fig. 13.

In advance of the chip cutting cylinders 31 and 32, the machine herein shown in Figs. 1, 2 and 3 provides cutting cylinders 40 and 41, which are carried on shafts 42 and 43 respectively, having intermeshing gears 44 and 45. The latter of said gears is in mesh with an intermediate gear 46 that is driven from the gear 35 of the chip removing cylinder 31. One of said cutting cylinders, here shown as the cylinder 41, Figs. 6 and 7, provides a substantially helical cutting blade 47, which is secured thereto in any suitable manner, as by means of a retaining screw 48 entering recess 49 in the periphery of said cylinder. Said blade 47 coöperates with the surface of opposite cutting cylinder 40 to sever the traveling web A on successive oblique lines 50, Fig. 13, whereby to form blanks which are substantially parallelogrammic in outline. The cutting cylinders 40 and 41 are rotated in the same relative directions as the cutting cylinders 21 and 22, by the gearing as above described, and the speeds of all said cutting devices are so timed that the lines of cut 50 will intersect the opposite corners of center cut 30 as well as the apexes of those notches 28 which are directly in line with each center cut 30, as clearly shown in Fig. 13. To this end the cutter blade 47 of cylinder 41 may be discontinuous, as shown in Fig. 6, a space being left between its two parts where it intersects the center cut 30, which has already been formed in the traveling web A.

Instead of separate pairs of cutting cylinders 21, 22 and 40, 41 respectively, the functions above described may be performed by a single pair of cylinders, the cutter carrying member of which would take the form shown in Figs. 11 and 12. Such a cylinder 51 would carry four edge cutters 27', corresponding to the edge cutters 27 of cylinder 22, and a cylinder cutter 29' corresponding to the center cutter 29 of cylinder 22. Said cylinder would also carry, preferably integral with cutters 27' and 29', the substantially helical cutter 47' corresponding to the cutter 47 of cylinder 41, and adapted to sever the web A into separate blanks, on oblique lines crossing said web, simultaneously with the cutting of the edge and center chips therefrom. After the operation of such a cutting cylinder 51, the chips would be removed in the manner heretofore described, or in any other suitable manner, and the blanks thus formed would thereby be completely separated from the web A, in precisely the same manner as shown in Fig. 13.

In advance of the cutting and chip removing devices as heretofore described, the machine of the present invention provides cylinders 52 and 53 for forwarding the separated blanks in the line of travel of web A, each blank being received into the bight of said rolls 52 and 53 in an oblique position. That is, the oblique line 50 constitutes the advancing edge of successive blanks in each 10 instance, said edge being formed by contiguous portions of one of the longitudinal flaps and one of the said flaps of the blank, as shown clearly in Fig. 13. With the blanks traveling in this direction, with such 15 an oblique edge foremost, there is no way in which the same may be centered and squared for the subsequent gumming and folding operations of the machine, and the present invention contemplates such a 20 change in the direction of movement of the blanks as will permit of their advancement in a symmetrical relation to the machine as regards their projecting side, back and seal flaps, and at the same time retaining the 25 advantages incident to cutting and forming the blanks in the manner above described, with a minimum waste of stock.

To this end the cylinders 52 and 53 are rotated so as to advance the separated blanks 30 continuously through the machine, said cylinders being carried on shafts 54 and 55 respectively which have intermeshing gears 56 and 57. The former of said gears is in mesh with an intermediate gear 58 that is driven 35 from the gear 44 of cutting cylinder 40, whereby the cylinders 52 and 53 are rotated in unison, in the same direction relatively as the previously described forwarding, cutting and chip removing cylinders to move the 40 blanks in substantially the same direction as the web A. The requisite change in direction, or partial rotation of the separated blanks, is effected by devices in advance of the cylinders 52 and 53, as hereinafter 45 described, and for the purpose of releasing each blank, just prior to the commencement of this movement, one of said cylinders, in the present instance the cylinder 53, has a segmental cutaway portion 59. This portion 50 enables the blank to be drawn out of the bight of rolls 52 and 53 by the direction changing devices, when the advancing edge of said blank is seized thereby, as hereinafter described. It is to be understood, 55 however, that my invention is not confined to the particular means herein shown and described for releasing the blank from the bight of forwarding rolls 52 and 53, namely the segmental cutaway portion 59—it being 60 clear that any equivalent releasing means, such as a mechanism for momentarily separating said rolls at the proper period in their revolution, could as well be employed.

The direction changing devices for operation on the separated blanks consists in the

present instance of coacting frusto-conical rolls 60, 61 arranged with converging axes at an angle oblique to the parallel axes of the previously described blank advancing cylinders 52 and 53. Said rolls 60 and 61 are 70 carried on shafts 62 and 63 respectively, which are journaled in suitable brackets 64 and 65 supported on table 1. The shafts 62 and 63 carry intermeshing gears 66 and 67, which are slightly beveled to compensate for 75 the convergence of said shafts. The shaft 62 of lower roll 60 carries a bevel gear 68 which is in mesh with a bevel gear 69 on a transverse shaft 70, the latter being driven by bevel pinions 71 and 72 from a shaft 73. 80 The latter is rotated in synchronism with the blank cutting and advancing devices of the machine by a bevel gear connection 74, 75 with the main driving shaft 8.

The separated blanks as received in the 85 bight of conical rolls 60, 61 have their direction of advancement varied, by reason of the greater peripheral speed of the larger ends of said rolls, as will be understood. The blanks are swung gradually through the 90 path indicated by the broken lines B, B, Fig. 13, their motion of translation being continued during their rotation, so that they finally assume the position indicated at C, Figs. 1 and 13, in which the projecting side 95 and longitudinal flaps are symmetrically disposed about the rectangular portion which defines the shape of the completed envelop or inclosure. In this position their advance is continued, in a straight line, by means of 100 coacting cylinders 76 and 77, Fig. 1, which are journaled in the side frames 5 and 6 with their axes at right angles to the axes of cylinders 52 and 53. The cylinders 76 and 77 are substantially the counterparts of cylinders 105 52 and 53, in that one of the former, in the present instance cylinder 77, has a segmental cutaway portion 78, which prevents said cylinders from seizing the advancing edge of the blank until the turning movement of the latter to bring it into the position C has been completed. Obviously, any equivalent means for accomplishing this same result could be employed. The cylinders 76 and 77 coöperate in advancing the 110 blank to the centering, squaring, gumming and folding devices of the machine, which form no part of the present invention, and are therefore unnecessary to describe. Said cylinders 76 and 77 are rotated by suitable 115 intermeshing gears, one of which, 79, is shown in Fig. 1 as being driven from a pinion 80 on shaft 81, the latter having a bevel gear connection 82 and 83 with shaft 70.

For facilitating the blank turning action 120 of conical rolls 60, 61, I provide coacting pairs of short cylindrical rolls 84, 85 and 86, 87 which are located respectively on opposite sides of said conical rolls, between the same and the adjacent pairs of cylinders 130

52, 53 and 76, 77 respectively. Said rolls 84 and 85 are carried on shafts 88 and 89 respectively, having intermeshing gears 90 and 91. The former of said gears is driven 5 by an intermediate gear 92 which is in mesh with gear 56 of cylinder 52, whereby the rolls 84 and 85 are rotated continuously in the same relative directions as cylinders 52 and 53. Said rolls 84, 85 are considerably 10 larger than the cylinders 52, 53, whereby they may be placed in close proximity to the conical rolls 60, 61, in order to insure the feeding of the edge of each separated blank to the bight of said conical rolls near 15 the outer larger ends of the latter. One of the rolls 84, 85, in the present instance the upper roll 85, has a segmental cutaway portion 93 similar to the portion 59 of cylinder 53, whereby the release of a blank is effected 20 when the latter is seized by the conical rolls 60, 61. The rolls 86, 87 are substantially counterparts of the rolls 84, 85, one of them, in the present instance the roll 87, having a 25 segmental cutaway portion 94 which prevents said rolls from seizing the blank until the latter has been released by the conical rolls 60 and 61. Said rolls 86, 87 are driven by intermeshing gears 95, 96 respectively, Fig. 3, one of which is in mesh with the gear 30 80 that is used to drive the gears 79 of rolls 76 and 77.

One of the conical rolls, in the present instance roll 61, has a segmental cutaway portion 97, which becomes operative to release the blank from the bight of said rolls 35 at the end of their turning operation thereon, just before said blank is seized in the bight of rolls 86, 87. In the operation of the above described mechanism, the separated blanks are each in turn moved continuously into the conical rolls 60, 61, and the final rolls 84, 85 operate to swing the outer end or edge of the blank while remaining inoperative with respect to its inner end or edge. The latter partakes of the 40 gradual movement of translation which is accomplished by the smaller inner ends of conical rolls 60, 61, and is not operated upon by the rolls 86, 87 which act only on the more rapidly moving outer end or edge. The segmental cutaway portion 93 releases the blank from the bight of rolls 84, 85 just as the blank is seized in the bight of conical rolls 60, 61, and the segmental cutaway portion 45 97 releases the blank from said conical rolls just as said blank is seized by rolls 86, 87. The latter complete the wide swinging movement of the outer end or edge of the blank, and thereafter the forward edge is seized in the bight of rolls 76, 77 and the blank is advanced into the position C for the operation of centering, squaring, gumming and folding.

It will be seen that the successive blanks, 50 as cut obliquely from the web A, have their

speed of advancement in the direction of said web gradually reduced as they come into the bight of conical rolls 60, 61. Simultaneous with their reduction in speed in the direction of web A, there is a combined 70 movement of translation and rotation by said conical rolls and by the short rolls 84, 85 and 86, 87 which carries the blanks through a curved path, whereby they come into symmetrical relation to the direction 75 of advance of the final forwarding rolls 76, 77.

I claim,

1. The combination with means for continuously advancing a web of paper, of 80 means for forming blanks from said web during its continuous advancement, means for advancing said blanks, conical rolls with axes arranged diagonally to the direction of advancement of said blanks, and means for 85 releasing the blanks from said blank advancing means upon their engagement by said conical rolls.

2. The combination with means for continuously advancing a web of paper, of 90 means for forming a blank from said web during its continuous advancement, an initial and a final means for forwarding the blank in different directions, conical rolls with their axes arranged diagonally to the 95 first and final directions of movement of said blank, and means for releasing the blank from said conical rolls upon its engagement by said final blank forwarding means.

3. The combination with means for cutting parallelogrammic blanks from a continuously advancing web of paper, of means for forwarding said blanks, conical rolls for rotating a blank in transit through a 105 predetermined angle, and means for forwarding said blank after rotation.

4. The combination with means for cutting parallelogrammic blanks from a continuously advancing web of paper, of cylindrical segmental blank advancing rolls, conical segmental rolls with axes arranged diagonally to the first and final directions of advance of the blank for rotating said blank in transit through a predetermined 110 angle in the plane of advance of said blank, and cylindrical segmental rolls for forwarding said blank after rotation.

5. The combination with means for continuously advancing a web of paper, of 120 means for forming blanks from said web during the continuous advancement of said web, means for continuously advancing said blanks, conical rolls with axes arranged diagonally to the first and final directions 125 of advance of said blanks, and blank forwarding rolls following said conical rolls.

6. The combination with blank cutting means, of means for advancing the blanks, segmental conical rolls with axes arranged 130

- diagonally to the first and final directions of advance of said blanks, for rotating said blanks through an angle less than a right angle, and means for forwarding said blanks 5 in a direction substantially at right angles to their first direction of advance.
7. The combination with means for continuously advancing a web of paper, of blank cutting means for forming blanks substantially parallelogrammic in outline from said web, conical rolls with axes arranged diagonally to the initial direction of movement of said blanks, for rotating said blanks in transit into position for a new direction 10 of travel, and means for continuously forwarding said blanks in said new direction.
8. The combination with cylindrical blank forwarding rolls, of diagonally extending 15 conical segmental rolls for rotating a blank through an angle less than a right angle, 20 and cylindrical segmental blank forwarding rolls following said conical rolls for forwarding said blank in a direction substantially at right angles to the first direction of advance of said blank. 25
9. The combination with blank cutting means, of diagonally extending segmental conical rolls for rotating a blank in transit at high speed through an angle less than a right angle in the plane of its advance into 30 position for a new direction of travel.

Dated this 7th day of Aug. 1917.
ABRAHAM NOVICK.
